US00D929482S

(12) **United States Design Patent** (10) **Patent No.:** **US D929,482 S**
(45) **Date of Patent:** **** Aug. 31, 2021**

(54) **CAMERA**

(71) Applicant: **Dolby Laboratories Licensing Corporation**, San Francisco, CA (US)

(72) Inventors: **Christine Anna Livaudais**, San Francisco, CA (US); **Vincent Voron**, Menlo Park, CA (US); **Samuel James Fleming Carr**, San Francisco, CA (US); **Peter Michaelian**, San Francisco, CA (US)

(73) Assignee: **Dolby Laboratories Licensing Corporation**, San Francisco, CA (US)

(**) Term: **15 Years**

(21) Appl. No.: **29/691,744**

(22) Filed: **May 18, 2019**

(51) LOC (13) Cl. **16-01**

(52) U.S. Cl.

USPC **D16/202**

(57) **CLAIM**

The ornamental design for a camera, as shown and described.

DESCRIPTION

FIG. 1 is a perspective view of a camera showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the camera in which the design is embodied that form no part of the claimed design.

1 Claim, 6 Drawing Sheets
